[57] **CLAIM**

The ornamental design for a multi-use cordless inflator, as shown and described.

DESCRIPTION

FIG. 1 is a perspective view of a multi-use cordless inflator showing my new design;

FIG. 2 is a first side view of the multi-use cordless inflator;

FIG. 3 is a first end view of the multi-use cordless inflator;

FIG. 4 is a second side view of the multi-use cordless inflator;

FIG. 5 is a second end view of the multi-use cordless inflator;

FIG. 6 is a top view of the multi-use cordless inflator; and,

FIG. 7 is a bottom view of the multi-use cordless inflator.

Any broken lines within the FIGS. showing the environment are for illustrative purposes only and form no part of the claimed design.
